UNITED STATES PATENT OFFICE.

JOHN F. MARTENS, OF CINCINNATI, OHIO, ASSIGNOR TO REDWAY & BURTON,
OF SAME PLACE.

DESIGN FOR THE ORNAMENTATION OF COOKING-STOVES.

SPECIFICATION forming part of Design No. 17,459, dated July 19, 1887.

Application filed June 4, 1887. Serial No. 240,343. Term of patent 3½ years.

To all whom it may concern:

Be it known that I, JOHN F. MARTENS, of Cincinnati, county of Hamilton, State of Ohio, have invented and produced a new and useful Design for the Ornamentation of Cooking Stoves and Ranges, which is fully set forth and described in the following specification and accompanying illustrations, forming part thereof.

10 The several features of my design consist in the adaptation to the several parts of the stove of the general features of my design, the whole forming a harmonious and complete design.

15 The several parts of the stove thus decorated are the following: the front door, the panel under the ash-pit, the feed-door of the fire-chamber, the oven-door, the panels of the hot closet and reservoir at rear of the stove, the skirting between the feet of the stove, the column between the stove proper and warming-oven, and the pipe-shelf and accompaniments.

20 Figures 1, 2, 3, and 4 represent the several styles of stoves to which my design is applied.

25 The general features of the design are best illustrated in the oven-door and in the feed-door of the fire-chamber. These doors are made in the well-known style of bonneted doors with rounded edges. The background is ornamented with small polygonal figures *a* in low relief, presenting the general appearance of a scaly skin like that of the alligator.

30 On the rounded edges of the door this scaly background becomes continuous with the conventional lines of water-waves *b*, within which are occasional flame-like figures *d*. The extreme edge of the door is decorated with more highly conventionalized water-lines *b'*. The lower edge of the door is not rounded, and is decorated with a line of inverted-U-shaped 35 figures, *c*. The largest portion of the door is covered by a projecting panel-frame, *D*, whose top is outlined by a triple curve, and whose upper portion is filled in with a conventional leaf-pattern in open-work. The lower part of the panel is left blank to receive an ornamental tile. There also appears on the 40 oven-door between the panel and the handle a conventional leaf and flower pattern, *E*, springing from a horizontal stem, *e*. The 45 feed-door to the fire-chamber presents the same background, the same rounded edges with

water-lines, and the same line of inverted-U-shaped figures at the bottom as are found in the oven-door. It is, moreover, decorated with the dragon-head *F* in low relief and side elevation.

55 The front door has the scale-like background shown in the other two doors, and the curved edges are also decorated with the water-lines *b b'*, the former being confined to the top of the door. In the middle of this door appears a conventional front view of an owl's head, *G*, in low relief. To each side of the owl's head, also in low relief, is a conventionalized twig, *H*, bearing berries.

60 The panel *I* below the ash-pit is raised, and bears no other decoration than the water-lines *b b'* at the ends.

65 The bonneted panel *J* and door *K* of the hot closets at the rear of the stove are each 70 decorated with the scale-like background. The upper panel, *J*, has the water-lines *b b'* at top, but only the water-lines *b'* at the sides. The water-lines *b'* also appear at the sides of the door *K*. The lower edge of the door *K* is 75 decorated with the inverted-U-shaped figures *c*. In the center of the panel *J* is an elevated annular frame to receive a decorated tile. The center of the door *K* is decorated with a head, *k*, in front view, low relief, half human half fiend, with conventionalized hair and beard.

80 When the warming-closet is omitted, the reservoir at the rear is supported on the bracket *P*, which is decorated with the alligator-skin background and raised scroll-work. When one or both of the hot chambers at the rear of the stove are employed, the vertical columns *R* and *S* between the stove and the hot chamber are decorated. In the present design the 85 column *R* is made into a rounded beading relieved by curved grooves. The column *S* is decorated with the U-shaped figures *c*.

85 Below the edge of the stove proper, and extending from foot to foot on the four sides of the stove, I have placed the downwardly-projecting skirting *L*, having free edge below. These skirtings *L* not only complete the finish 90 of the stove, and thus add to its general attractiveness, but they also form a good location for decoration. The particular decoration which I have used on these skirtings in

Open

- the present design is to cover them with the scale-like background used in the other parts of the design, and to place in the center of the panel, in low relief, a conventionalized head, *l*, in front view partly surrounded by a conventionalized wreath. At the ends of each of the skirtings *L* a conventionalized leaf design, *l'*, is placed, which has the effect of joining more intimately the feet and skirtings.
- 10 In the larger sizes of stoves or ranges, as shown in Fig. 4, the pipe-shelf *M* is added. The pipe-shelf *M* is supported by a standard, which consists of a central standard, *M'*, and lateral arms *M''*. The standard *M'* is curved outwardly and has its surface decorated in general like the other surfaces of the stove. The background has the alligator-skin decoration *a* and the highly-conventionalized water-lines *b*' at the sides, and at the bottom a modification of the inverted U-shaped figures *c*. In the center of the standard *M'* is a frame, *m*, to hold an ornamental or name panel. The panel *m* is decorated with flame-like figures *m'*. Below the shelf *M* the arms *M''* are decorated with conventionalized leaf pattern *m''*, the background being as before. Above the shelf the arms *M''* have the alligator-skin background and conventionalized leaf pattern *m'* at the ends. The standard *M'*, above the shelf, is further decorated with the frame *m'*, carrying an ornamental tile. At each side of the standard *M'* is a low shelf, *N*, mounted on a standard, *N'*, decorated with scroll-work, *n*.
- What I claim as new, and desire to secure by Letters Patent, is—
1. In a design for a stove, the ornamentation of surfaces with alligator-skin background *a*, conventionalized water-lines *b*' and U-shaped figures *c*, substantially as shown and described.
2. In a design for a stove, the ornamentation of the oven-door, consisting of background *a*, water-lines *b*' and leaf figure *E*, substantially as shown and described.
3. In a design for a stove, the ornamentation of the oven door, consisting of a background, *a*, water-lines *b*' flame figure *d*, leaf figure *E*, and panel *D*, substantially as shown and described.
4. In a design for a stove, the ornamentation of the door of the fire-chamber, consisting of background *a*, water-lines *b*' and head *F*, substantially as shown and described.
5. In a design for a stove, the ornamentation of the front door, consisting of background *a*, water-lines *b*' owl-head *G*, and sprigs *H*, substantially as shown.
6. In a design for a stove, the ornamentation of the skirting *L* with background *a*, face *l*, and leaf-work *l'*, substantially as shown.
7. In a design for a stove, the ornamentation of the panel *J*, consisting of background *a*, water-lines *b*' and circular tile frame, substantially as shown and described.
8. In a design for a stove, the ornamentation of the hot-chamber door *K*, consisting of background *a*, water-lines *b*', figures *c*, and head *k*, substantially as shown.
9. In a design for a stove, the ornamentation of the columns *R* and *S*, substantially as shown and described.
10. In a design for a stove, the ornamentation of the pipe-shelf support *M'* *M''*, consisting of the background *a*, water-lines *b*', frame *m*, with flame-lines *m'*, and frame *m''*, on the standard *M'*, and background *a* and scrolls *m''* 75 and *m'*, on arms *M''*, substantially as set forth.
11. In a design for a stove, the ornamentation of the bracket-supports *N'*, consisting of the scroll-work *n'*, substantially as shown.
12. In a design for a stove, the ornamentation of the oven-door, fire-chamber door, front door, and skirtings *L*, substantially as shown and described.
13. In a design for a stove, the ornamentation of the oven-door, fire-chamber door, front door, skirting *L*, panel *J*, and bracket *P*, substantially as shown and described.
14. In a design for a stove, the ornamentation of the oven-door, fire-chamber door, front door, skirting *L*, and panels *J* and *K*, substantially as shown and described.
15. In a design for a stove, the ornamentation of the oven-door, fire-chamber door, front door, skirting *L*, panels *J* and *K*, and pipe-shelf support *M'* *M''*, substantially as shown 95 and described.
16. In a design for a stove, the ornamentation of the oven-door, fire-chamber door, front door, skirting *L*, panels *J* and *K*, pipe-shelf support *M'* *M''*, and shelf-supports *N'*, substantially as shown and described.
